DESIGN FOR A MAIL BOX PEDESTAL

William Henry Mahoney, Hingham, Mass.

Application May 17, 1934, Serial No. 51,823

Term of patent 7 years

To all whom it may concern:

Be it known that I, WILLIAM H. MAHONEY, a citizen of the United States, residing at Hingham, in the county of Plymouth and State of Massachusetts, have invented a new, original, and ornamental Design for a Mail Box Pedestal, of which the following is a specification, reference being had to the accompanying drawing, forming a part thereof.

The figure is a perspective view of my new design.

I claim:

The ornamental design for a mail box pedestal substantially as shown.

Signed at Hingham, in the county of Plymouth and State of Massachusetts, this 9th day of May, 1934.

WILLIAM HENRY MAHONEY.
